HENRY C. PRITHAM, OF BRIDGEPORT, CONNECTICUT, ASSIGNOR TO UNION METALLIC CARTRIDGE COMPANY, OF BRIDGEPORT, CONNECTICUT, A CORPORATION OF CONNECTICUT.

WATERPROOF SHOT-CARTRIDGE.

1,144,379.

Specification of Letters Patent. Patented June 29, 1915.

Application filed March 3, 1915. Serial No. 11,838.

To all whom it may concern:

Be it known that I, HENRY C. PRITHAM, a citizen of the United States, residing at Bridgeport, county of Fairfield, State of Connecticut, have invented an Improvement in Waterproof Shot-Cartridges, of which the following is a specification.

This invention relates to shot cartridges and has for its object to provide cartridges of this character that shall be more completely waterproof than any heretofore known to the trade.

It is of course well understood that the rolled paper tubes from which shot cartridges are made, are made waterproof in various ways and that the top wads may be waterproofed, and it is furthermore well understood that the top wads in shot cartridges are secured in place and the charges retained therein by crimping, so called, the end of the paper tube; in other words, turning the end of the tube over inward and closing it down upon the wad. Cartridges made in this manner, however, have been found subject to deterioration owing to the fact that under certain conditions moisture will find its way under the crimp and around the edge of the wad causing swelling of the wad and crimp, so as to render it difficult and sometimes impossible to insert the cartridge in a gun chamber and sometimes permitting escape of the shot charge.

My present invention enables me to entirely overcome these difficulties and to provide paper shot cartridges which in addition to the ordinary qualities of high grade cartridges are made completely waterproof at the crimp. This I accomplish by treating the crimp ends of the cartridges with a suitable waterproof material which covers the wad and completely fills and covers the crevice at the intersection of the crimped end of the tube with the wad.

In the accompanying drawing forming a part of this specification, the view is an elevation of a shot cartridge with the crimp end in section, showing the top wad and also the manner in which the end of the shell is crimped down upon it to retain the charge in place and also showing the application of my present invention thereto.

10 denotes the paper tube, 11 the top wad, 12 the crimp of the end of the shell upon the

wad, and 13 waterproof material which covers the top wad and completely covers 55 over and effectually closes the crevice between the wad and the end of the crimp.

The special waterproof material used is unimportant so far as my present invention is concerned. It is simply required that the material used be of a character to permit its convenient application. I may use for example a nitro-cellulose solution, or a solution of shellac in wood alcohol. There are numerous other materials that will accomplish the result just as well. It is likewise wholly immaterial how the material is applied. If dropped upon the wads or if applied by means of a cork-tipped mandrel, surface tension will cause the material to 70 spread over the surface of the wads, to fill in and cover the crevice at the intersection of the crimp and the wad and to work outward more or less upon the inner face of the crimp. This is especially true if the cartridge is rotated or if a mandrel dipped in the material is rotated in close proximity to the top wad. Any desired color may be given to the material, but at present I am using a transparent material which permits 75 the quality of powder and weight of the charge and the size of shot and weight of the charge, which are commonly printed upon the outer face of the top wads, to be read clearly through the material, it being understood of course that the materials used will 80 quickly harden after application.

Having thus described my invention I claim:—

A shot cartridge comprising a paper shell 90 and a top wad retained in place by crimping the end of the shell thereupon, the wad being covered and the crevice between the wad and the crimp being filled and covered by a suitable transparent waterproof material 95 through which printing on the wad may be read and which prevents moisture from passing under the crimp and around the edge of the wad.

In testimony whereof I affix my signature in presence of two witnesses.

HENRY C. PRITHAM.
